UNITED STATES PATENT OFFICE.

MAX KURTH, OF FRANKLIN, PENNSYLVANIA, ASSIGNOR TO INGERSOLL-RAND COMPANY,
OF NEW YORK, N. Y., A CORPORATION OF NEW JERSEY.

VARIABLE-VOLUME AIR-COMPRESSOR.

No. 909,427.

Specification of Letters Patent.

Patented Jan. 12, 1909.

Application filed December 11, 1907. Serial No. 405,991.

To all whom it may concern:

Be it known that I, MAX KURTH, citizen of the United States, residing at Franklin, in the county of Venango and State of Pennsylvania, have invented certain new and useful Improvements in Variable-Volume Air-Compressors, of which the following is a specification, reference being had therein to the accompanying drawing.

10 The object, construction and operation of my invention are herein fully set forth, reference being had to the accompanying drawings which form a part hereof, and in which:

Figure 1 represents a fluid compressor cylinder and its adjacent parts, partly in side elevation and partly in section, embodying my invention. Fig. 2 represents the fluid compressor cylinder and its adjacent parts, partly in top plan and partly in longitudinal 20 central section. Fig. 3 is a transverse section taken in the plane of the line A—A of Fig. 1, looking in the direction of the arrows, and Fig. 4 is a transverse section taken in the plane of the line B—B of Fig. 1, looking in 25 the direction of the arrows.

The same reference letters indicate identical parts in the several views.

To those familiar with the operation of air compressors and the character of service in which they are employed, it is a well known fact that it is necessary to employ some means whereby the delivery or output of the compressor may be automatically regulated in accordance with the amount of compressed air being used, and which amount varies considerably in some classes of service. It is also a well known fact that, in nearly all classes of compressed air service, compressed air is delivered by the compressor to a receiver, which is practically a storage reservoir from which the air is drawn for application and service. It is by the pressure of air in said reservoir that nearly or quite all of the devices which regulate the volume of delivery of the compressor are actuated. By far the larger number of such devices at present employed are of the type known as "unloaders," the function of which is when the pressure in the receiver rises to a pre-determined maximum point, to hold either an inlet or a discharge valve open so that ingress and egress of air to and from the cylinders will take place through the same valve, by which operation no additional air is delivered 55 to the receiver during the unloaded period,

which continues until the pressure in the receiver falls below said maximum point by reason of the withdrawal of air therefrom. The application of an unloader to an air compressor, however, does not bring it within 60 the class known as variable volume compressors, for the reason that when the unloader is dormant the entire product of the compressor is being delivered to the receiver, and when the unloader is acting no air whatever is being delivered to the receiver; on the other hand, a variable volume compressor is one adapted to deliver to the receiver not only the full volume of its produce but any percentage thereof according to the requirements of the service.

It is the object of my invention to provide a device, by the application of which to any air compressor, the same may be converted into a variable volume compressor. In general terms I accomplish said object by attaching to the cylinder of the compressor a clearance chest provided with a plurality of chambers, one or more of which chambers may be automatically placed in communication with the clearance space in the cylinders, thus increasing the volume of said space, and correspondingly decreasing the efficiency or relative output of the compressor.

In the drawings I have shown the application of my device to a double acting compressor, and the following description relates to such application, but those skilled in the art to which my invention appertains will readily understand that it is equally applicable to a single acting compressor.

The construction of my device is substantially as follows: I provide a clearance chest 1 which contains a plurality of chambers 2, 3, and 2' 3', and at each end of said chest 1 I form a cylinder 4 and 4' each closed at either end and having a piston 5 and 5' operable therein; said cylinders are in longitudinal alinement and their respective pistons 5, 5' are connected together by means of the piston rod 6, which passes through stuffing boxes 7, 7' in the respective heads of the cylinders; from said cylinders ports 2^p, 3^p and 2'^p, 3'^p lead to the respective chambers of the clearance chest; the interior of each of said cylinders 4, 4' is placed in communication with the clearance space 3, 3' in the respective end of the air compressor cylinder 9, by means of the ports 10, 10'; the port 10 being at the inner end of cylinder 4, and 110

port 10' being at the outer end of cylinder 4'; ports 10 and 10' are normally covered by the pistons 5 and 5' respectively.

For the purpose of retaining pistons 5 and 5' in the normal position shown in Fig. 1, I employ a bell crank 11, one arm of which engages the piston rod 6 and to the other arm of which is attached a lever 12, upon which is adjustably mounted a counterweight 13; 10 approximate to the fulcrum of said bell crank 11 is located a cylinder 14, having therein a piston 15, and into the rear of cylinder 14 is introduced a pipe 16 which leads to the receiver into which air is delivered by 15 the compressor; a connecting rod 17 connects piston 15 with bell crank 11 in such a manner that the action of said weight and the action of said piston when actuated by the receiver pressure, are opposed to one another. 20 The operation of my device is substantially as follows: When the pressure in the receiver has reached a point sufficiently high that its action upon piston 15 will overcome the action of the counterweight 13— 25 said point of pressure being determined by the position of said counterweight upon lever 12—weight 13 will be caused to rise and the action of the bell crank will carry rod 6 and the thereto attached pistons, in the direction indicated by the arrow, and ports 10 and 10' will be uncovered, thus placing chambers 3 and 2' in communication with the clearance space in the respective ends of the air compressor cylinder; this action 30 causes a portion of the compressed charge in the compressor cylinder to enter its respective clearance chamber, and when the piston starts upon its intake stroke, the compressed air in said chamber will be exhausted 35 therefrom, or in other words, the pressure in said chamber must first fall to the normal atmospheric pressure, before free or atmospheric air will be taken into the compressor through the inlet valve, hence the actual discharge from the compressor into the receiver will be relative to the amount of air entering the clearance chest during the compression stroke and returning therefrom during the suction stroke. If, under this condition, the 40 pressure in the receiver continues to rise, further action thereon upon piston 15 will cause, as aforesaid, a further action of the bell crank and a corresponding movement of pistons 5 and 5', and ports 2' and 3' will be 45 uncovered this adding the additional volume of chambers 2 and 3' to the clearance space, which will cause a corresponding reduction 50 of the output of compressed air from the compressor. 55 A is a by-pass by means of which pressure is established upon both sides of the pistons 5—5' to balance the same.

Having thus described my invention, what I claim as new and desire to secure by Letters Patent is:

1. In a variable volume fluid compressor, the combination with the fluid compressor cylinder and the receiver for the compressed fluid generated by said compressor, of a clearance chest having therein a plurality of compartments and means for successively placing the compartments in communication with the clearance space in said cylinder as the pressure in the receiver rises to different predetermined points. 75

2. In a variable volume fluid compressor, the combination with the fluid compressor cylinder and the receiver for the compressed fluid generated by said compressor, of a clearance chest having therein a plurality of compartments and means for successively placing the compartments in communication with the clearance space in said cylinder as the pressure in the receiver rises to different predetermined points and to successively 80 close communication between the said compartments and clearance space in said cylinder as the pressure in the receiver falls to different predetermined points. 85

3. In a variable volume fluid compressor, 90 the combination with the fluid compressor cylinder and the receiver for the compressed fluid generated by said compressor, of a clearance chest having therein a plurality of compartments and automatic means for successively 95 placing the compartments in communication with the clearance space in said cylinder as the pressure in the receiver rises to different predetermined points. 100

4. In a variable volume fluid compressor, the combination with the fluid compressor cylinder and the receiver for the compressed fluid generated by said compressor, of a clearance chest having therein a plurality of compartments and automatic means for successively placing the compartments in communication with the clearance space in said cylinder as the pressure in the receiver rises to different predetermined points and to successively 105 close communication between the said compartments and clearance space in said cylinder as the pressure in the receiver falls to different predetermined points. 110

5. In a variable volume fluid compressor, the combination with the fluid compressor 115 cylinder and the receiver for the compressed fluid generated by said compressor, of a clearance chest having therein a plurality of compartments and fluid pressure controlled means for successively placing the compartments in communication with the clearance space in said cylinder as the pressure in the receiver rises to different predetermined points. 120

6. In a variable volume fluid compressor, 125 the combination with the fluid compressor cylinder and the receiver for the compressed fluid generated by said compressor, of a clearance chest having therein a plurality of compartments, and fluid pressure controlled 130

means for successively placing the compartments in communication with the clearance space in said cylinder as the pressure in the receiver rises to different predetermined points and to successively close communication between the said compartments and clearance space in said cylinder as the pressure in the receiver falls to different predetermined points.

10 7. In a variable volume fluid compressor, the combination with the fluid compressor cylinder and the receiver for the compressed fluid generated by said compressor, of a clearance chest having therein a plurality of compartments and automatic means for placing one of said compartments in communication with the clearance space in said cylinder when the pressure in said receiver reaches a predetermined point and for successively placing the remainder of said compartments in communication with said clearance space when the pressure in said receiver continues to rise.

8. In a variable volume fluid compressor, the combination with the fluid compressor cylinder and the receiver for the compressed fluid generated by said compressor, of a clearance chest having therein a plurality of compartments and automatic means for placing one of said compartments in communication with the clearance space in said cylinder when the pressure in said receiver reaches a predetermined point and for successively placing the remainder of said compartments in communication with said clearance space when the pressure in said receiver continues to rise and for successively closing communication between said compartments and clearance space in said cylinder as the pressure in the receiver falls.

I testify whereof I affix my signature in presence of two witnesses.

MAX KURTH
